UNITED STATES PATENT OFFICE

JAMES HALL TAYLOR, OF OAK PARK, ILLINOIS

METHOD OF MAKING NOZZLES

Application filed April 11, 1928. Serial No. 269,092.

My invention relates to a new and improved method of making nozzles of the type commonly used in connection with steam boilers and consisting of a flaring neck with a flange at each end thereof.

The accompanying sectional drawings illustrate, step by step, a complete method, from billet to finished article, embodying my invention.

10 In these drawings:

Fig. 1 is a view of the original billet or blank;

Fig. 2 is a view showing the billet between the first set of dies;

15 Fig. 3 shows the beginning of the operation in the second set of dies;

Fig. 4 shows the second set of dies in mid position;

20 Fig. 5 shows the second set of dies in final position;

Fig. 6 shows the added action of a shearing die;

Fig. 7 shows the beginning of the action in the third set of dies;

25 Fig. 8 shows the completion of the action of Fig. 7;

Fig. 9 shows the added action of a further die; and

Fig. 10 shows the finished article.

30 The original wrought metal blank 11 is shown in Fig. 1. This blank is subjected to the action of the dies *a* and *b* illustrated in Fig. 2, the result being the formation of a circular body 12 with a V-shaped projecting flange comprising the inner portion 13, which is curved, the outer portion 14, which is preferably straight, and the flashing 15.

The billet is then placed in a circular die *c*, the effective internal diameter of which is 40 substantially the same as the inner diameter of the flashing 15 as indicated at *x*. This permits the shoulder which marks the periphery of the flange to be set down within the die *c*, as illustrated. The die *d* moves relatively to the die *c*, downwardly as indicated by the arrows in Figs. 3, 4 and 5, the first result being the inward working of the portion 13 of the flange and the consequent upsetting at the junction between the portions 13 and 14, as indicated in Fig. 4, this being due to the en-

gagement of the periphery of the flange portion 14 with the inside of the die *c*, the same being held appropriately in that position by the engagement of the flashing 15 with the top of the die *c*.

55 The next result is the partial straightening of the flange, as indicated in Fig. 5, this being due to the continued movement of the die *d* and the engagement of the flashing 15 with the inner rim of the die *c*, some stretching taking place during this operation.

The next action is the bringing down of the shearing die *e*, as indicated in Fig. 6, the flashing 15 being taken off in this operation.

65 The billet is then inverted and placed upon the stool *f* of die *g*, as indicated in Fig. 7, the concentric female die *h* being then brought down over the body of the billet so that the inner rounded portion *h'* thereof will first engage the outside of the portion 13 of the flange. As this action continues the portion 13 and the junction between it and the portion 14 are stretched somewhat, and continued action brings the portion 14 down upon the face of the die *g* to complete the operation 70 as indicated in Fig. 8.

75 With the dies *g* and *h* in the position shown in Fig. 8, die *i*, shown in Fig. 9, is brought down upon the top of the body portion 12 of the billet to force the same into the annular recess *h*-2 in the die *h*, thus forming the flange 16.

80 The remaining central portion of the body 12, indicated at 17, is then punched out, and any flashing on the periphery of the flange 85 removed.

The result is the finished article shown in Fig. 10, comprising the flaring circular neck 13, the large diameter flange 14 at one end thereof and the small diameter flange 16 at 90 the other end thereof.

I claim:

1. The process of making nozzles, which comprises forming a circular body of metal with a circular projecting flange of V-shaped cross-section, and then, while maintaining the periphery of said flange, moving said body in a direction to move the outer portion of said flange toward position at right angles to the axis of said circular body of metal to swing 95

100

the inner portion of said flange inwardly, and removing the central portion of the body.

2. The process of making nozzles, which comprises forming a circular body of metal with a circular projecting flange of V-shaped cross-section, and then, while maintaining the periphery of said flange, moving said body in a direction to move the outer portion of said flange toward position at right angles to the axis of said circular body of metal to swing the inner portion of said flange inwardly and to upset said flange at the junction of the two portions thereof, and removing the central portion of the body.

15 3. The process of making nozzles, which comprises forming a circular body of metal with a circular projecting flange of V-shaped cross-section, and then, while maintaining the periphery of said flange, moving said body in the direction of the open side of the V to bring the outer portion of said flange into position at right angles to the axis of said circular body of metal, to swing the inner portion of said flange inwardly, and then to bring said outer portion into oblique position opposed to its original position, and then applying inward pressure to said inner portion and bringing said outer portion into position at right angles to said axis, and removing the central portion of the body.

35 4. The process of making nozzles, which comprises forming a circular body of metal with a circular projecting flange of V-shaped cross-section, and then, while maintaining the periphery of said flange, moving said body in a direction to move the outer portion of said flange toward position at right angles to the axis of said circular body of metal to swing the inner portion of said flange inwardly, 40 then smashing down said body portion to form a second flange, and then removing the central portion of said body portion.

45 5. The process of making nozzles, which comprises forming a circular body of metal with a circular projecting flange of V-shaped cross-section, then placing the billet in an annular die to maintain the periphery of said flange and moving said body through said die while the periphery of said flange is in engagement with the inner rim of said annular die, and removing the central portion of the body.

55 6. The process of making nozzles, which comprises forming a circular body of metal with a circular projecting flange of V-shaped cross-section having a flashing upon the periphery thereof, then placing the billet in an annular die with the periphery of said flange engaging the inner rim thereof and the flashing engaging the face thereof, and moving said body through said die while the periphery of said flange is in such engagement with said annular die, and removing the central portion of the body.

65 7. The process of making nozzles, which

comprises forming a circular body of metal with a circular projecting flange of V-shaped cross-section having a flashing upon the periphery thereof, then placing the billet in an annular die with the periphery of said flange 70 engaging the inner rim thereof and the flashing engaging the face thereof, and moving said body through said die while the periphery of said flange is in such engagement with said annular die and shearing off said flashing by cooperation between a shearing die and said annular die, and removing the central portion of the body.

80 8. The process of making nozzles, which comprises forming a circular body of metal with a circular projecting flange of V-shaped cross-section having a flashing upon the periphery thereof, then placing the billet in an annular die with the periphery of said flange 85 engaging the inner rim thereof and the flashing engaging the face thereof, and moving said body through said die while the periphery of said flange is in such engagement with said annular die and shearing off said flashing by cooperation between a shearing die 90 and said annular die, then applying pressure to the inner portion of said flange to swing it further inwardly and to decrease its thickness and bringing the outer portion of said flange into position at right angles to the 95 axis thereof and removing the central portion of the body.

100 9. The process of making nozzles, which comprises forming a circular body of metal with a circular projecting flange of V-shaped cross-section having a flashing upon the periphery thereof, then placing the billet in an annular die with the periphery of said flange 105 engaging the inner rim thereof and the flashing engaging the face thereof, and moving said body through said die while the periphery of said flange is in such engagement with said annular die and shearing off said flashing by cooperation between a shearing die 110 and said annular die, then applying pressure to the inner portion of said flange to swing it further inwardly and to decrease its thickness and bringing the outer portion of said flange into position at right angles to the 115 axis thereof, smashing down said body and removing the central portion thereof.

120 10. The process of making nozzles, which comprises forming a circular body of metal with a circular projecting flange of V-shaped cross-section, and then, while engaging the periphery of said flange, moving said body in a direction to move the outer portion of said flange toward position in the plane of said periphery to reduce the inner diameter of said outer portion, and removing the central portion of the body.

125 11. The process of making nozzles, which comprises forming a circular body of metal with a circular projecting flange of V-shaped cross-section, and then, while confining the 130

periphery of said flange, moving said body
in a direction to move the outer portion of
said flange toward position in the plane of
said periphery to upset said flange at the
5 junction of the two portions thereof, and re-
moving the central portion of the body.

In witness whereof, I hereunto subscribe
my name this 3rd day of April, 1928.

JAMES HALL TAYLOR.
